DRINKING GLASS

Hyman J. Warsager, Newark, N. J.

Application February 7, 1956, Serial No. 40,071

Term of patent 14 years

(Cl. D36—8)

Fig. 1

I claim:

The ornamental design for a drinking glass, as shown.
